[57] CLAIM

The ornamental design for a front deflector shield, as
shown and described.

DESCRIPTION

FIG. 1 is a perspective view of a front deflector shield
showing my new design in position of use on a vehicle
which is fragmentarily shown in broken lines for illus-
trative purposes only and forms no part of the claimed
design;

FIG. 2 is a front elevational view thereof;

FIG. 3 is a top plan view thereof;

FIG. 4 is an enlarged side elevational view thereof; and,

FIG. 5 is an enlarged sectional view taken along lines
5—5 of FIG. 2.
